UNITED STATES PATENT OFFICE.

CHARLES T. DRAPER, OF CLEVELAND, OHIO, ASSIGNOR TO THE DRAPER MANUFACTURING COMPANY, OF CLEVELAND, OHIO, A CORPORATION OF OHIO.

SHEET-METAL RECEPTACLE.

1,134,730.

Specification of Letters Patent.

Patented Apr. 6, 1915.

Application filed August 22, 1912. Serial No. 716,412.

To all whom it may concern:

Be it known that I, CHARLES T. DRAPER, citizen of the United States, residing at Cleveland, in the county of Cuyahoga and 5 State of Ohio, have invented certain new and useful Improvements in Sheet-Metal Receptacles, of which the following is a specification.

My invention relates to improvements in 10 sheet-metal receptacles, and more particularly to barrels formed of sheet steel with reinforced chimes.

The object of my invention is to provide 15 a receptacle which will be durable and remain liquid-tight after severe usage.

Steel barrels, as previously constructed, have been provided with reinforcing chimes, but these structures have depended upon the closeness and rigidity of engagement 20 thereby, for maintaining the joints at the heads. Moreover, in the prior structures, a severe blow upon the head or chime was liable to open or spring the joint or seam, 25 between the head and body of the barrel, thereby causing leakage. Accordingly, I have sought to remedy these defects:

First, by making a liquid-proof, double-locked joint between the head and barrel body, independent of the reinforcing means.

Second, I have provided an auxiliary seal, 30 in the form of a plastic cement, inserted within the annular seam or double-locked joint, preferably employed at the heads of the barrel.

Third, I have provided a peculiarly shaped 35 wrought iron ring, having a protective over-turned lip and an annular recess. Within this annular recess the upturned rims of the head and barrel-body are adapted to be 40 rolled, adjacent to the head, for tightening the ring against the head, in position to receive pressure from within or without the barrel.

Fourth, my improved barrel preferably is 45 provided with two centrally positioned annular ribs, which are of greater diameter than the chimes of the barrel, and form a bilge whereon said barrel is adapted to roll.

50 Further details of my improved construction may be more readily explained, by making reference to the accompanying drawings, wherein:—

Figure 1, is a side view, sectionally broken 55 away, illustrating a sheet metal barrel em-

bodying my improvement. Fig. 2, is an enlarged detail view, showing the annular joint in section, with the protective rim inserted interiorly thereof. Fig. 3, is a similar view, showing the flange depressed, and 69 Fig. 4, is another similar view showing a section of the completed joint.

Throughout the figures of the drawings, I have employed the same character of reference to indicate similar parts.

It will be understood that the sheet metal barrel, herein shown, is typical merely, of the structural features of barrels, containing-drums or metallic receptacles for any purposes whatsoever, and particularly those 70 requiring a hermetic seal, for avoiding losses through evaporation and leakage. The body portion *a* is of substantially cylindrical form; being constructed from sheet-metal of suitable gage, and provided with circumferential spaced ribs *a' a'*, forming the bilge of said barrel. The heads comprise convex disks *b b* having upturned rims of such diameter as to fit snugly within the ends of the body portion. The edges of said body 75 portion first receive a coating of any suitable plastic cement, such as rubber, gutta-percha or glue compositions, and double-locked joints *b' b'* are formed, embracing both edges and affording four thicknesses of 80 metal at said joints. Any inequalities or imperfections in the joint, will, of course, be rectified by the cement *c*, which fills the minute spaces between the surfaces and edges 85 of the sheet metal. Wrought iron rings *d d* are then forced down, with their bases *d' d'* 90 resting upon the heads *b b*, and their flanges *d'' d''* are then bent over the double-locked joints, so as to form reinforced chimes for the barrel. It will be observed, that said 95 rings afford substantially parallel engaging walls for the double-locked seams, which are left open for inspection, by providing flanges which partially inclose the edges. Obviously, any leakage, even with light oils, 100 gasoline and the like, may be at once located and remedied in the construction shown, without impairing the efficiency of the reinforcing ring.

In order to secure each ring in place, and 105 also tighten it against the head of the barrel, I have provided upon its inner vertical face, adjacent to the base *d'*, the annular groove *d²*. The bodies of the projecting rims of the barrel-head and barrel, are then rolled in 110

the said groove d^2 , which serves to tighten the ring within the head, and maintain it rigidly in position. The flange d'' may be simultaneously or subsequently rolled, if desired, to tighten the same over the double-locked joint. Ordinarily, a joint of this character would be sufficient for maintaining a seal of the barrel-head, but with heavy gage metal, and particularly in view of the re-rolling operation, if said joint has been sprung, it is desirable that a plastic seal be provided in addition, whereby any immediate or subsequent strains of the joint, if of minor character, will be provided for, instead of depending upon a metal-to-metal, or soldered joint.

By reason of the supporting ribs a' a'' , afforded for the barrel, when it is rolled, the seams at the heads are not subjected to any strains from this source.

Having now described with some detail, a steel barrel exemplifying and embodying my invention, I claim as new and desire to secure by Letters Patent, the following:

- 25 1. In a permanent closure for metallic receptacles, the combination with a substantially cylindrical body-portion formed of sheet-metal, of a disk-like sheet-metal closure-member inserted within the end of said body-portion; the same having an upturned rim with its edges united with the edges of the body-portion to form a double-locked joint, and a protective ring inserted within said closure-member having a down-turned 35 flange covering the side of the double-locked joint, and a continuous annular recess wherein the rims of said closure-member and body-portion are forced, substantially as set forth.
2. In a sheet-metal barrel, the combina-

tion with a substantially cylindrical body-portion formed of sheet-metal and centrally ribbed to provide a bilge, of disk-like sheet-metal heads inserted within the ends of said body-portion; the same having upturned rims with their edges united with the edges of the body-portion to form double-locked annular joints, and supporting rings inserted within the rims to bear annularly against the heads, each of said rings having a flange partially inclosing the corresponding double-locked joints and continuous annular recess wherein the rims of the head and barrel are rolled or depressed to lock the parts closely together, substantially as set forth.

3. In a permanent closure for metallic receptacles, the combination with a substantially cylindrical body-portion formed of sheet metal, of disk-like sheet metal closure-members inserted within the ends of said body-portion; the same having upturned rims united with the edges of the body-portion, and forming liquid-proof joints therewith, and protective rings inserted respectively within said closure-members, the same having down-turned exterior flanges, covering the sides of the liquid-proof joints, and annular recesses positioned beyond said down-turned flanges, wherein the rims of said closure-members and body portion are rolled to secure parts together, substantially as set forth.

In testimony whereof I do now affix my signature in the presence of two witnesses.

CHARLES T. DRAPER.
